(57) CLAIM

The ornamental design for a golf club head with grooves, as shown and described.

DESCRIPTION

FIG. 1 is a front elevational view of the golf club head with grooves herein;

FIG. 2 is an enlarged view of the region located within the square in FIG. 1;

FIG. 3 is an enlarged view of the region located within the circle in FIG. 2; and,

FIG. 4 is a cross-sectional view of the golf club head shown in FIG. 2 along lines 4-4.

The broken lines are included for the purpose of illustration and form no part of the claimed design.
